(57) **CLAIM**

The ornamental design for an eye mask as shown and described.

DESCRIPTION

FIG. 1 is a front perspective view from above of the claimed eye mask according to one embodiment;

FIG. 2 is a rear perspective view from above of the claimed design of FIG. 1;

FIG. 3 is a front view of the claimed design of FIG. 1;

FIG. 4 is a rear view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1; and

FIG. 8 is a bottom view of the claimed design of FIG. 1;

FIG. 9 is a front perspective view from above of the claimed eye mask according to another embodiment;

FIG. 10 is a rear perspective view from above of the claimed design of FIG. 9;

FIG. 11 is a front view of the claimed design of FIG. 9;

FIG. 12 is a rear view of the claimed design of FIG. 9;

FIG. 13 is a left side view of the claimed design of FIG. 9;

FIG. 14 is a right side view of the claimed design of FIG. 9;

FIG. 15 is a top view of the claimed design of FIG. 9; and,

FIG. 16 is a bottom view of the claimed design of FIG. 9.

The broken lines depict portions of the article and form no part of the claimed design.

1 Claim, 16 Drawing Sheets
